UNITED STATES PATENT OFFICE

2,436,015

CIGARETTE ROLLING DEVICE

Joseph M. Morris, San Bernardino, Calif.

Application December 21, 1945, Serial No. 636,326

3 Claims. (Cl. 131—47)

1

This invention relates to a cigarette rolling device, and more particularly to a manually operated device of this character adapted for the rolling of individual cigarettes.

A primary object of this invention is the provision of an improved cigarette rolling device adapted particularly for home use, whereby a cigarette may be rolled with a minimum of difficulty and effort, the resulting product being substantially equivalent to that of a machine-made cigarette.

A further object of the invention is the provision of such a device which may be readily operated in either direction, either by the right or left hand, and in accordance with the desires of the operator.

A still further object of the invention is the provision of such a device which is sturdy and durable in construction, reliable and efficient in operation, and relatively simple and inexpensive to manufacture and assemble.

Other objects will in part be obvious and in part be pointed out as the description of the invention proceeds, and shown in the accompanying drawings, wherein there is disclosed a preferred embodiment of this inventive concept.

In the drawing:

Figure 1 is a top plan view, partly broken away, showing one form of device embodying the instant invention.

Figure 2 is a sectional view taken substantially along the line 2—2 of Figure 1, as viewed in the direction indicated by the arrows, certain concealed portions thereof being indicated by dotted lines.

Similar reference characters refer to similar parts throughout the several views of the drawings.

Referring now to the drawing in detail, there is generally indicated at 10 a main supporting frame member comprised of a base 11 and upturned side portions 12. The side portions 12 are provided with elongated oppositely disposed L-shaped slotted apertures 13 having adjacent depending legs 14. Seated in the slots 13 for longitudinal movement therein are supporting axles 15 which support wooden rolls 16 of relatively large diameter. The extremities of the axle 15 extend through suitable apertures 19 in a rectangular movable frame 17 adapted to move the rollers 16 in a manner to be more fully described hereinafter, and have positioned on the squared extremities thereof finger knobs 18 by means of which the rollers may be rotated. Positioned intermediately of the side portions 12 and relatively

2

between the extremities of the slots 13 are opposite aligned apertures which support two axles 20, which in turn carry rollers 21 of relatively small diameter as compared to the diameter of the rollers 16.

A flexible band 22 of rubber or the like is adapted to surround the rollers 16 and overlie the rollers 21 fitting loosely therearound to provide slack, as indicated at 23 (see Fig. 2).

10 A paper guide 25 comprised of a pivotal wire loop having its lower extremities 24 suitably journaled in apertures in the upper portions of the side walls 12 is also provided and positioned between the two rollers 21.

15 It is to be noted that washers 26 may, if desired, be positioned between the side walls 12 and the rectangular roller-moving member 17.

From the foregoing the operation of the device should now be readily understandable.

20 The rollers 16 are moved by the frame 17 to the desired position, either as shown in Figure 2, or oppositely, the position being limited by the length of the slots 13. It is to be noted that the frame 17 serves to hold the rollers 16 in proper spaced relation during the cigarette rolling operation. The belt 22 is then positioned to provide slack, as indicated at 23, to form a transverse pocket to hold the tobacco. When the wooden rollers 16 are pushed back by means of the frame 17, the

25 pocket is forced back and up against one of the small rollers 21. Then the paper can be inserted into the pocket in the space between the wooden roller 16 and the adjacent roller 21, and the cigarette rolled and completed by operation of the proper knob 18. The paper guide 25 can be flipped on its extremities 24 toward either end of the device, so that the cigarette may be formed in either desired direction of movement of the frame 17.

30 From the foregoing it will now be seen that there is herein provided an improved cigarette making machine, which accomplishes all the objects of this invention, and others, including many advantages of great practical utility and commercial importance.

35 As many embodiments may be made of this inventive concept, and as many modifications may be made on the embodiment hereinbefore shown and described, it is to be understood that all matter herein is to be interpreted merely as illustrative and not in a limiting sense.

I claim:

40 1. In a device of the character described, the combination of a frame including side walls having elongated slots therein, axles journaled in

45 50

said slots, rollers carried by said axles, an auxiliary frame having apertures therein, said axles passing through said apertures whereby said rollers are maintained in spaced relation, a flexible belt surrounding said rollers, and auxiliary rollers spaced between and above said first-mentioned rollers and journaled in said side walls.

2. In a device of the character described, the combination of a frame including side walls having elongated slots therein, axles journaled in said slots, rollers carried by said axles, an auxiliary frame having apertures therein, said axles passing through said apertures whereby said rollers are maintained in spaced relation, a flexible belt surrounding said rollers, auxiliary rollers spaced between and above said first-mentioned rollers and journaled in said side walls, and a paper guide positioned above and between said last-mentioned rollers.

3. In a device of the character described, the combination of a frame including side walls having elongated slots therein, axles journaled in said slots, rollers carried by said axles, an auxiliary frame having apertures therein, said axles

passing through said apertures whereby said rollers are maintained in spaced relation, a flexible belt surrounding said rollers, auxiliary rollers spaced between and above said first-mentioned rollers and journaled in said side walls, and a paper guide positioned above and between said last-mentioned rollers, said slots being provided with depending portions in which said axles are adapted to seat selectively.
